In Sweden October 16, 1935

6 Claims. (Cl. 122—235)

The last years' development in the steam boiler technique is distinguished, among other things, by endeavours toward a better utilization of the active material of the boilers than has been possible in boilers of older types, whereby so-called radiation boilers have been arrived at, with furnaces surrounded more or less completely by water-cooled steel walls. These furnace walls are generally made from tubes which are connected in some way or other into the circulation system of the boiler. For constructional reasons, the tubes, however, cannot be placed too close to one another, but must be spaced a sufficient distance so that the requisite strength is obtained, among other things, in the walls of the domes or the collecting vessels to which the tubes are connected unless a great number of tube boxes are employed. To the extent in which the furnace wall is not entirely constituted by heat absorbing fire surface, its capability of utilizing the radiant heat will be reduced. It has therefore been attempted in various ways to make the whole wall heat-absorbing, *inter alia* by filling the intermediate spaces between the tubes with heat-conducting material for transferring to the tubes the heat absorbed by such material.

A method as hitherto known of filling the intermediate spaces between the tubes in the tube walls of the radiation furnaces is to weld metal onto the tubes, for instance so-called fin tubes. At high temperatures in the furnaces, certain disadvantages occur, however, inasmuch as the flat fins cannot be made sufficiently wide, without becoming unduly heated in the outer edges, whereby the edges are burned and the function of the fins is impaired. Also, cracks are apt to form in the edges of the fins, said cracks propagating inwardly to the tube wall, so that the latter may ultimately burst.

The present invention refers to an arrangement for the provision of preferably water-cooled walls in furnaces or the like, particularly for steam generators (steam boilers) consisting of tubes which are in known manner connected at their ends to domes or other collecting vessels, the invention being principally characterized in that the intermediate spaces between the tubes, which are connected at their both ends directly to the collecting vessels, are filled, entirely or in part, by one or more tubular members substantially parallel to the tubes, said members being connected at their both ends to the tubes at points located outside the connecting places between the tubes and the collecting vessels. It is of particular advantage to connect the tubular

members, which in the following are termed side tubes, in parallel, as regards the flow, to an intermediate portion of the appertaining main tube. One or more side tubes may be arranged on the one or on both sides of a main tube.

The arrangement according to the invention is serviceable not only for the generation of steam, or other gas by the evaporation of water or other liquid, but also for other heating apparatus in which the heat-absorbing medium is constituted, for instance, by some gas, such as steam in a superheater or air in an air preheater.

The invention will be described more closely hereinbelow with reference to the accompanying drawings.

Fig. 1 shows a vertical section of a steam boiler provided with walls covered by tubes in accordance with the invention. Fig. 2 shows a wall portion according to Fig. 1 to a larger scale. Fig. 3 is a section on line III—III in Fig. 2. Fig. 4 is a section on line IV—IV in Fig. 2. Fig. 4a shows a modification to a larger scale. Figs. 5—8 illustrate, in the same manner as Fig. 2, various methods of connecting the side tubes to the main tubes. Figs. 9 and 10 show sections of other types of tubes.

The steam boiler shown in Fig. 1 is suited for oil- and/or carbon powder firing, but obviously the invention is just as applicable to grate-fired steam boilers.

In Fig. 1, the side walls of a suitable brickwork are designated by 1 and 1a respectively, the visible remote head wall being denoted by 2. 3 designates a steam dome which is connected through a downcomer 4 to the lower collecting vessel 5, which extends in parallel to the wall 1 on the lower side of the latter. Arranged on the upper side of the wall 1a and parallel to the latter is an upper collecting vessel 6. Arranged on the head wall 2 is a lower collecting vessel 7 and an upper collecting vessel 8. The other collecting vessels 5 and 7 are connected to the upper collecting vessels 6 and 8 respectively by means of tubes 9 forming an internal covering of the walls 1, 1a, 2 of the furnace chamber. Tubes 10 extend from the collecting vessel 6, and tubes 11 from the collecting vessel 8, to the steam space of the dome 3.

The tubes 9 covering the wall 1 have an extension 9a at the top, said extension running transversely over the furnace chamber to the collecting vessel 6. The tubes covering the wall 1a have an extension 9b at the bottom, the said extension running transversely over the lower

portion of the furnace chamber to the collecting vessel 5.

12 designates nozzles for the introduction of oil and/or carbon dust as well as secondary air 5 into the furnace chamber.

The tubes 9 are provided, at least at the portions located along the walls, with side tubes 13 arranged according to the invention.

From Fig. 2, which illustrates a portion of the 10 tube covering for the wall 2 to a larger scale, it will be seen that the tubes 9 may be secured in a normal manner, for instance by rolling, in the collecting vessels 7 and 8. Each tube 9 is provided with one or more, in this case two, 15 tubular members or side tubes 13 arranged along the tube, the side tubes being so dimensioned and located as to fill the intermediate spaces between the tubes 9 to a suitable extent. The side tubes open into the tube 9 in suitable places, 20 preferably in the proximity of the connection of the tube 9 to the collection vessels 7 and 8, in such a manner that liquid flowing from the one collecting vessel 7 out into a certain tube 9 will flow in parallel through both the tube 9 25 and its two side tubes 13. The portion of the fluid passing through the side tubes is returned to tube 9 in the proximity of the second collecting vessel 8, and flows into the latter through the connection of the tube 9 thereto. In 30 a wall made in this manner for a steam generator, the side tubes 13 are thus connected into the circulation system of the boiler. The side tubes 13 may be altogether free from their tube 9, except at the connecting points, where they 35 are connected, for instance by welding, with the tube 9 in apertures provided for this purpose in the walls of the tube 9, or the side tubes 13 may be attached to the tube 9, for instance by welding, at one or more points or along the 40 whole of the tube 9, as appears at 14 in Fig. 4a.

In the embodiment disclosed in Fig. 5, the tubes 9 are provided with one side tube 13 only. According to Fig. 6, there are two side tubes 13 on each tube 9, but in difference from Fig. 2, 45 both side tubes are arranged on the same side of the main tube. In the same manner, three or more side tubes may be arranged. If desired, these side tubes may be connected directly with each other.

50 In the embodiments above described, the side tubes 13 are connected, as regards the flow, in parallel to the portion of the main tube 9 located between the connecting points of the side tubes.

It is also possible to arrange a side tube 13a, 55 Fig. 7, in such a manner that it will communicate at the top with a tube 9, and at the bottom with another adjacent tube 9. It is also possible in a similar manner to arrange two or more side tubes 13a between the tubes 9, as shown in Fig. 8.

60 The tubes 9 are always arranged at a sufficient distance from each other, in order that the openings for their attachment in the collecting vessels 7 and 8 respectively shall not be located too near one another, whereby they would weaken 65 the walls of the collecting vessels.

In a reconstruction of an old boiler, no alteration whatever is required in the collecting vessels. The only thing required is that apertures be provided in the walls of the tubes 9 for the 70 connection of the side tubes 13. In this case, it is more suitable to make the side tubes 13 of a smaller diameter than that of the main tubes 9, in order to permit the tubes to be located in the same plane. On the whole, it is always the most 75 suitable to make the side tubes thinner than the

tube 9, so that the latter need not be weakened too much by too large connecting openings in the walls.

The arrangement with side tubes above described may also be used in tubes that are provided with flanges. In this case, the side tubes 13 are disposed in front of the flanges, so that the latter will be protected against direct heat radiation which is detrimental to the life thereof. The side tubes are disposed in such a 10 manner, however, as not to prevent heat radiation to the main tubes 9. Such an arrangement is shown in section through the tubes, in Fig. 9, in which the main tube is again denoted by 9. On both sides of the tube 9, flanges 15 are arranged in 15 the manner illustrated in the figure. The position of the side tubes 13 also appears from the drawing. The side tubes are not arranged diametrically opposite one another, but are located athwart in front of the flanges 15, so that the 20 latter are protected as far as possible against direct heat radiation. Finally, Fig. 10 shows a tube provided with flanges 15, said tube being adapted to be arranged in a corner of the furnace. The adjacent tubes 9 are disposed in rows 25 extending in the directions of the flanges 15.

In the examples illustrated, the collecting vessels are shown as being straight. They may of course just as well be made arcuate, which may be the case, for instance, if the furnace chamber 30 is made round.

In the example according to Fig. 1, the tubes 9 arranged at the walls 1 and 1a are provided with side tubes on the vertical portion only, while the tube portions 9a and 9b, respectively, extending transversely over the furnace have no side tubes. These portions 9a, 9b may also, however, be provided with side tubes, provided that all tube portions 9a are not located in the same plane so that the flow of the flue gases is 40 prevented.

I claim:—

1. In furnace walls for steam generators, the combination of spaced main tubes, collecting vessels in communication with said tubes at both 45 ends of the latter, longitudinal flanges on said tubes, and side tubes extending alongside of the main tubes, athwart in front of said flanges, said side tubes being connected at their both ends to the main tubes at points located outside the connecting points between the main tubes and the 50 collecting vessels.

2. In furnace walls for steam generators, the combination of spaced main tubes, collecting vessels in communication with said main tubes at both 55 ends of the latter, and side tubes in the spaces between said main tubes, said side tubes communicating with the main tubes and being mechanically connected to the main tubes along the whole of their length.

3. In furnace walls for steam generators, the combination of spaced main tubes, collecting vessels in communication with said main tubes at both 60 ends of the latter, and side tubes in the spaces between said main tubes, said side tubes communicating with the main tubes and being mechanically connected to the main tubes along a portion of their length.

4. In furnace walls for steam generators, the combination of spaced main tubes, collecting vessels, said main tubes extending between and communicating at both ends with said collecting vessels and being of constant cross section areas and having radial openings between their connecting points with said collecting vessels, and 75

side tubes of smaller diameter than that of the main tubes and placed in the spaces between the main tubes, said side tubes being directly connected at both ends thereof to the main tubes at said openings.

5. In furnace walls for steam generators, the combination of spaced main tubes, collecting vessels, said main tubes extending between and communicating at both ends with said collecting 10 vessels and being of constant cross sectional areas and having pairs of opposite radial openings between their connecting points with said collecting vessels, and side tubes of smaller diameter than that of the main tubes and placed on two opposite sides of the main tubes, said side tubes being directly connected at both ends thereof to the main tubes at said openings.

6. In furnace walls for steam generators, the combination of spaced main tubes, collecting vessels, said main tubes extending between and communicating at both ends with said collecting vessels and being of constant cross sectional areas 5 and having pairs of opposite radial openings between their connecting points with said collecting vessels, and side tubes of smaller diameter than that of the main tubes and placed on two opposite sides of the main tubes, said side tubes 10 being directly connected at both ends thereof to the main tubes at said openings the side tubes being connected in parallel to the intermediate portion of the respective main tubes.
